US00D902165S

(12) **United States Design Patent** (10) **Patent No.:** **US D902,165 S**
Johanson et al. (45) **Date of Patent:** **** Nov. 17, 2020**

(54) **TARGET PROFILE FOR A PHYSICAL VAPOR DEPOSITION CHAMBER TARGET**

(71) Applicant: **APPLIED MATERIALS, INC.**, Santa Clara, CA (US)

(72) Inventors: **William R. Johanson**, Gilroy, CA (US); **Kirankumar Neelasandra Savandaiah**, Bangalore (IN); **Prashant Prabhakar Prabhu**, Karwar (IN)

(73) Assignee: **APPLIED MATERIALS, INC.**, Santa Clara, CA (US)

(**) Term: **15 Years**

(21) Appl. No.: **29/726,094**

(22) Filed: **Feb. 28, 2020**

Related U.S. Application Data

(62) Division of application No. 29/639,953, filed on Mar. 9, 2018, now Pat. No. Des. 877,101.

(57) **CLAIM**

The ornamental design for a target profile for a physical vapor deposition chamber target, as shown and described.

DESCRIPTION

FIG. 1 is a top perspective view of a target profile for a physical vapor deposition chamber target showing our new design;

FIG. 2 is a bottom perspective view thereof;

FIG. 3 is a top plan view thereof;

FIG. 4 is a bottom plan view thereof;

FIG. 5 is a right elevation view thereof;

FIG. 6 is a left elevation view thereof;

FIG. 7 is a front elevation view thereof;

FIG. 8 is a back elevation view thereof; and,

FIG. 9 is an enlarged cross sectional view taken along line 9-9 in FIG. 4.

The dashed lines in FIGS. 1-9 represent unclaimed environment and form no part of the claimed design.

1 Claim, 7 Drawing Sheets
